CLAIM

The ornamental design for a display panel, as shown and described.

DESCRIPTION

FIG. 1 is a front, top, and right side perspective view of a display panel showing our new design;
FIG. 2 is a front view thereof;
FIG. 3 is a rear view thereof;
FIG. 4 is a top plan view thereof;
FIG. 5 is a bottom plan view thereof;
FIG. 6 is a right side view thereof;
FIG. 7 is a left side view thereof;
FIG. 8 is a perspective view with a panel tilted; and,
FIG. 9 is a right side view with a panel tilted.
The features shown in broken lines in the drawings depict environmental subject matter only and form no part of the claimed design.
